DESIGN FOR A FINGER RING OR SIMILAR ARTICLE

Andrew Schwartz, Providence, R. I.

Application January 17, 1942, Serial No. 105,267

Term of patent 3½ years

To all whom it may concern:

Be it known that I, Andrew Schwartz, a citizen of the United States of America, residing in Providence, county of Providence, State of Rhode Island, have invented a new, original, and ornamental Design for a Finger Ring or Similar Article, of which the following is a specification, reference being had to the accompanying drawing, forming a part thereof.

Fig. 1 is a perspective view of the finger ring or similar article showing my new design;

Fig. 2 is a side elevation thereof;

Fig. 3 is an elevation looking at the finger ring or similar article in the direction indicated by the arrows 3—3 in Fig. 2; and

Fig. 4 is a plan view looking at the finger ring or similar article in the direction indicated by the arrow lines 4—4 in Fig. 3.

I claim:

The ornamental design for a finger ring or similar article substantially as shown.

ANDREW SCHWARTZ.
